UNITED STATES PATENT OFFICE.

LOGAN OWEN, OF MACON, GEORGIA.

ROVING-GUIDE TRAVERSE-MOTION.

SPECIFICATION forming part of Letters Patent No. 770,440, dated September 20, 1904.

Application filed February 9, 1904. Serial No. 192,759. (No model.)

To all whom it may concern:

Be it known that I, LOGAN OWEN, a citizen of the United States, residing at Macon, in the State of Georgia, have invented certain new and useful Improvements in Roving-Guide Traverse-Motions, of which the following is a full, clear, and exact description, reference being had to the accompanying drawings, forming a part of this specification.

10 In my prior patent, No. 727,191, dated May 5, 1903, I have described a device wherein the roving-guide is driven from the builder-motion by connections between the guide and lifting rail.

15 It is well known that in the various forms of slubbers, speeders, fly-frames, and the like the lift-shaft for the builder-motion is given a varying rotating motion first in one and then in the other direction. For instance, assuming that the maximum rotative movement is one revolution, said shaft then revolves in the opposite direction to very near the starting-point or to a point approximately one-half the diameter of the roving from the starting-

20 point. Then it moves in the first direction to its maximum travel less one-half the diameter of the roving, then back again to the starting-point less one-half the diameter of the roving, continuing to decrease the travel at each up-

25 ward and downward movement of the builder-motion until the minimum travel is reached, at which point the bobbin is full, forming the bevel on each end of the bobbin. When this process is completed, the builder-motion has

30 again reached a point to give its maximum travel, the filled bobbin is doffed and an empty bobbin put in its place, and the process is repeated. In the present embodiment of my invention I have taken advantage of this vary-

35 ing rotative motion of the lift-shaft to impart to the roving-guide the varying motion desired to prevent undue wearing of the drawing-rolls and in the present instance have provided the roving-rod with two guide-eyes

40 close together, which lead between the same pair of drawing-rolls, whereby under the varying movement of the roving-rod the paths of movement of the rovings will be caused to

overlap or cross each other near the center of the rolls.

50 In the drawings, Figure 1 is an elevation of a detached portion of a spinning-frame embodying one form of my present invention, some of the parts being omitted to more clearly illustrate the mechanical construction, 55 which more particularly pertains to the invention. Fig. 2 is a like view of a slightly-modified form of the invention. Fig. 3 is still another modified form to be described.

55 Referring to Fig. 1, the main frame A may 60 be of any usual or desired construction to provide therein suitable bearings *a* for the lift-shaft B, said lift being given rotative movement to varying degrees first in one and then in the other direction to properly lay the 65 yarn upon the bottom, as will be understood. Mounted upon the frame A are the usual drawing-rolls C, back of which is arranged the roving guide-rod D, movable longitudinally in suitable bearings, as *d*. The roving guide- 70 rod D is preferably provided with two guide-eyes *d'* and *d''* for each of the rolls C, whereby the eyes *d'* and *d''* guide a plurality of rovings between upper and lower drawing-rolls. Secured to the lift-shaft B is a beveled pinion *B'*, 75 which engages a segmental rack E, mounted to oscillate on a pivot *E'*, carried by a bracket *E''*. The part carrying the segmental rack E may for convenience of identification be termed the "rack-plate" F, the end thereof opposite the 80 rack E being connected to a rod *f* at *f'*, the opposite end of said rod *f* having a pivotal connection at *f''* with a lever *f''*. The lever *f''* is mounted on a pivot pin or stud *f''*, of any usual form, carried by suitable bracket-arms *f''*, 85 depending from the main frame A. In order that the lever-arm *f''* may be adjusted, the ends of the bracket-arms *f''* are slotted at *f''*. Connected to the end of the lever-arm *f''* opposite the pivotal connection *f''* is a rod *g*, 90 the upper end of which at *g'* connects with one arm, *g''*, of a bell-crank lever, the other arm of which, *g'''*, is provided with a slot *g''*, engaging the pin *g''* on the roving guide-rod. The bell-crank lever having the arms *g''* and 95 *g'''* is pivotally mounted upon a stand *g''*, which

has a slot g^7 for adjustment of the bell-crank lever, as will be obvious.

From the construction described it will be noted that as the lift-shaft B is rotated first in one and then in the other direction it will through the gearing connection of the pinion B' and rack E impart to the roving guide-rod D a reciprocating movement, and the length of each reciprocation of the roving guide-rod 10 will depend upon the degree of movement given to the lift-shaft B. The lift-shaft B has imparted to it by the usual builder mechanism varying degrees of rotation first in one and then the other direction, the maximum 15 of such rotative movement, however, usually, not exceeding one complete rotation of the lift-shaft, from which it will be obvious that the transverse movement of the roving guide-rod D will also vary as the movements im- 20 parted to the shaft are varied. The movement thus imparted to the roving guide-rod D will cause the paths of the rovings to be carried past the center of the drawing-rolls at each reciprocation, so as to equalize the 25 wear on each side of the center thereof.

It will be obvious, of course, that various 30 adjustments may be made in the connections between the lift-shaft B and the roving guide-rod D, so as to change the path or degree of reciprocation given to the roving guide-rod as desired. Changes may also be made in the 35 construction and the gearing connection between the lift-shaft and the roving guide-rod; but the essential characteristic of this feature of invention is in providing gearing connection of some character directly between the lift-shaft and the roving-rod to give reciprocal movement to the latter.

In Fig. 2 is illustrated a modified form of 40 the device where the lift-shaft B is provided with a gear B², secured thereon, said gear B² meshing with the rack B³ and said rack having suitable guide-lugs b for directing its up- 45 ward and downward movement under the re- verse rotative action of the lift-shaft. Connected to one end of the rack B³ is a lever b', pivoted at b² in the slotted bearing b³ of the bracket-arms b⁴, the end of said lever b' be- 50 ing connected at b⁵ with a rod b⁶, which at its opposite end engages a bell-crank lever g² g³, similar to that already described. From this 55 construction it will appear that as the lift-shaft is rotated first in one and then in the opposite direction it will move the rack B³ up and down and through the connections de- 60 scribed give the desired reciprocating move- ment of varying extent to the roving guide-rod D.

In Fig. 3 still another modified form of in- 60 vention is shown wherein the lift-shaft B is provided with a worm H, secured thereto, the said worm engaging the end of the lever H', the upper

end of said lever H' having a slot h² directly 65 engaging a stud h³, secured to the roving guide-rod D, whereby reciprocating move- 70 ment is imparted to the roving guide-rod direct from the lift-shaft B as the same is rotated first in one and then in the other direc- 75 tion.

It will be noted that the roving guide-rod in each of the forms of invention shown is given its traverse-motion through gearing connections from the lift-shaft and that the roving guide-rod contains a plurality of guide-eyes for each pair of drawing-rolls, the reciprocal movement of the roving guide-rod being such that the paths of movement of the rovings will by reciprocation of said rod be caused to pass the center point of each pair of drawing-rolls, and while I have shown the particular embodiment of my invention in the forms hereinbefore described I wish it to be understood that I do not regard my invention as limited to the details of structure disclosed, 85 which may be changed within wide limits, the essentials of the invention being gearing connection between the roving-rod and the lift-shaft for reciprocating the former and carrying the paths of the rovings to opposite sides 90 of the center of the drawing-rolls.

The lever and rod connections between the roving guide-rod and the gearing actuated by the lift-shaft B may be generally designated as an "actuator" and the form of such lever and rod connection or actuator may vary within wide limits, as will be obvious, without departing from the spirit of my invention.

Having thus described my invention, what I claim, and desire to secure by Letters Patent, is—

1. A roving-guide traverse-motion comprising a roving guide-rod through which the material is delivered to the drawing-rolls, an actuator therefor, a lift-shaft and means connect- 105 ing the lift-shaft and the actuator.

2. A roving-guide traverse-motion comprising the roving guide-rod for delivering the material to the drawing-rolls, an actuator therefor, a lift-shaft and gearing connections be- 110 tween the lift-shaft and the actuator.

3. A roving-guide traverse-motion comprising a roving guide-rod provided with a plu- 115 rality of eyes for each set of drawing-rolls, an actuator for said rod, a lift-shaft and gearing connections between the lift-shaft and actuator.

4. A roving-guide traverse-motion comprising a lift-shaft, a roving guide-rod for deliver- 120 ing the material to the rolls, an adjustable ac- tuator therefor to vary the path of movement of the roving-rod and gearing connection be- 125 tween the lift-shaft and the actuator.

5. In a device of the character described, the combination of a lift-shaft, a roving guide-rod provided with a pair of guide-eyes for each

set of drawing-rolls, an actuator for said roving guide-rod for causing the paths of movement of the rovings to pass the center of the drawing-rolls on each reciprocation, and positive connections between the lift-shaft and the actuator.

5 In testimony whereof I have hereunto af-

fixed my signature this 6th day of February, A. D. 1904.

LOGAN OWEN.
